UNITED STATES PATENT OFFICE.

FREDERICK F. GAINES, OF SAVANNAH, GEORGIA, ASSIGNEE BY ASSIGNMENT, TO AMERICAN ARCH COMPANY, OF NEW YORK, N. Y., A CORPORATION OF DELAWARE.

LOCOMOTIVE-BOILER FURNACE

1,138,061.

Specification of Letters Patent

Patented May 4, 1915.

Application filed July 24, 1913. Serial No. 789,964.

To all whom it may concern:

Be it known that I, FREDERICK F. GAINES, a citizen of the United States, and a resident of Savannah, in the county of Chatham and 5 State of Georgia, have invented certain new and useful Improvements in Locomotive-Boiler Furnaces, of which the following is a specification.

My invention relates to improvements in 10 locomotive boilers, and has particular reference to improvements in fireboxes or furnaces for locomotive boilers.

The object of my invention is to provide 15 a firebox construction whereby the efficiency of the firebox shall be increased; whereby the cost of construction and maintenance shall be decreased; and whereby the burning firebox gases shall be detained within the firebox a sufficient time to permit substantially perfect combustion to take place before the gases escape through the flues.

A further object of my invention is to 20 simplify the construction and installation of cross walls in locomotive boiler fireboxes, to reduce the maintenance cost thereof, and to provide a wall construction whereby the wall, once being installed, will remain in operative condition an indefinitely long time.

Further objects of my invention will appear hereinafter.

My invention consists of a locomotive boiler firebox, in combination with a refractory cross wall arranged in the forward part thereof, a bridge member extending 35 across the firebox and supported thereby having a shelf or ledge upon which the wall rests and is supported, and having an integrally formed buck stay plate extending upwardly over the forward face of the wall 40 and to which the wall is secured.

My invention further consists in a firebox having a cross wall arranged in its forward part rising from substantially the level of the grate, and a transverse bridge member 45 spanning the firebox and supported thereby, said bridge member consisting of an integrally formed wall shelf and buck stay plate adapted to hold the wall and to retain it in position.

50 My invention further consists in a support for cross walls in locomotive fireboxes, said support having a wall shelf portion and

a wall retaining plate portion integrally formed, and means for retaining said support in position in the firebox. 55

My invention further consists in a locomotive boiler firebox provided with a transverse refractory wall in its forward part, said wall having vertically arranged air inlet conduits, an integral wall shelf and wall-retaining plate supporting and retaining the wall in position, said shelf having openings admitting air into said conduits, and an integral transverse flange depending from the rear edge of the shelf and adapted to direct 60 air into said openings.

My invention also consists in the several arrangements and combinations of parts, and in the features of construction, by which the above and other objects are attained, and 70 all as hereinafter described and particularly pointed out in the appended claims.

My invention will be more readily understood by reference to the accompanying drawings, forming a part of this specification, and in which:

Figure 1 is a vertical central longitudinal section of a locomotive firebox equipped with a cross wall and embodying my invention; Fig. 2 is a vertical transverse section of the firebox on the line 2-2 of Fig. 1; Fig. 3 is a horizontal section of the cross wall on the line 3-3 of Fig. 1; Fig. 4 is a view similar to Fig. 1, showing a modified form of my invention; Fig. 5 is a transverse section on the line 5-5 of the firebox shown in Fig. 4; Fig. 6 is a horizontal section taken on the line 6-6 of Fig. 4; and Fig. 7 is a view similar to Fig. 6 showing another slight modification of my invention. 85 90

The function of cross walls in fireboxes is to prevent the direct flow of the gases of combustion from the grate to the flues, thus retaining the gases in the firebox a sufficient time to permit the completion of the combustion of the fuel before the gases escape through the flues, and causing the gases to circulate throughout the firebox, thereby efficiently imparting the heat thereof to the water in the boiler. 95 100

Cross walls as ordinarily built are expensive to install and also expensive to maintain for by reason of the extremely high temperature in which they are situated, and the

severe shaking, vibration and jarring to which they are subjected in use they soon disintegrate and fall to pieces. By means of my invention I am enabled to produce 5 cross walls in fireboxes which retain the advantageous features above noted and which substantially eliminate the defects which have appeared to be inherent heretofore in such walls.

10 A locomotive boiler firebox A, as illustrated in the drawings, consists of a flue sheet a^1 at the forward end, a rear sheet a^2 , a crown sheet a^3 and side sheets a^4 . Flues a^5 lead forward from the flue sheet, and the 15 rear sheet is provided with a fuel door or opening a^6 . The firebox is provided with a grate a^7 of usual construction. I provide a refractory cross wall B arranged in the forward end of the firebox spaced rearwardly from the flue sheet and forming between the wall and the flue sheet an auxiliary combustion chamber a^8 . The wall does not extend to the crown sheet, but a connecting passage a^9 is provided between the 20 top of the wall and the crown sheet through which the gases of combustion flow from the main combustion chamber a^{10} to the auxiliary combustion chamber a^8 . For supporting the wall in position I provide a transversely arranged wall support C. This wall support consists of a wall shelf c^1 arranged beneath the wall and extending from side to side in the firebox, an integrally formed wall-retaining plate c^2 rising from the 25 forward edge of the shelf in contact with the forward face of the wall, and also extending substantially from side sheet to side sheet. At the ends of the shelf I provide downwardly extending plates or brackets c^3 30 adapted to be bolted to the side walls of the firebox by means of bolts c^4 . I also provide a downwardly extending flange c^4 joined to the rear edge of the shelf, and extending across the firebox. This flange or plate c^4 35 serves to strengthen the shelf and I extend its lower edge below the lower edge of the firebox, causing it to serve to direct air into and through conduits provided in the wall. I further provide the bridge member C with 40 a depending flange, or plate c^5 joined to the forward edge of the shelf, and adapted to form part of the floor of the auxiliary combustion chamber. For the purpose of strengthening the wall-retaining plate c^2 I 45 provide it with integral vertically extending ribs c^6 merging at their lower ends into the depending wall c^5 . I preferably build the wall of several transverse rows b^1 of bricks 50 arranging them in the form of a vertical wall, the forward face of which is in contact with the wall-retaining plate c^2 . The lower row of bricks rests directly upon the shelf c^1 and for the purpose of retaining this lower or first row in position, I provide, upon the rear edge of the shelf, an 55 upwardly extending flange or ledge c^7 which contacts with the rear face of the lower row of bricks and holds it upon the shelf. I preferably form the several bricks with central projections b^2 upon their upper surfaces and with complementary grooves or openings b^3 on their lower surfaces, whereby the several rows of bricks are interlocked together. For the purpose of retaining the wall in position against the plate c^2 I provide a row of cap bricks b^4 formed to overlap the upper edge of the wall and provided on their rear edges with depending flanges b^7 adapted to overlap the upper edge of the wall and on their front edges with similar 60 depending portions b^6 adapted to engage the forward face of the plate c^2 . These cap bricks thus formed serve to interlock the upper end of the wall with the upper end of the retaining plate c^2 and thereby retain the wall in position. In addition to this interlocking of the cap bricks with the wall and plate, I sometimes secure the bricks of the top row of the wall to the upper part of the plate by means of bolts b^8 . As thus described the wall serves the function of preventing a direct flow of the gases of combustion from the fuel bed to the flues and the gases of combustion are thereby retained in the firebox longer than they would be held therein if they were allowed to flow directly from the fuel bed to the flues. The wall as constructed and maintained is substantially permanent, being held against disintegration by means of the integrally 65 formed shelf and retaining plate. As a further feature, I provide the wall with vertically extending air conduits or passages b^9 which extend from the lower edge thereof and are adapted to admit air to the firebox from the upper part of the wall through its rear face and beneath the overhanging portion of the cap bricks b^4 . I provide several of these passages so that the air is admitted to the firebox in a plane extending substantially across the box and serving to add air to the gases of combustion as they rise from the fuel bed and to thereby effect the substantially perfect oxidation of the fuel. For the purpose of admitting air into the conduits I provide the shelf c^1 with air inlet openings c^8 , one for each conduit and the depending flange or plate c^4 serves to force air upwardly through said openings, and into and through said conduits when the locomotive is running forward. For the purpose of completing the floor of the lower end of the auxiliary combustion chamber I provide a horizontal plate c^9 which is joined at its rear edge to the forward edge of the depending plate c^5 and at its forward edge to the forward water leg of the boiler. This plate extends from side to side of the firebox and closes the lower end of the auxiliary combustion chamber.

As the gases of combustion enter the auxiliary combustion chamber through the contracted passage a^9 they expand and their speed is reduced, and consequently they are forced to deposit any burden of unburned fuel or cinders which they may be carrying. These cinders collect in the lower part of the auxiliary combustion chamber, and for the purpose of conveniently removing these cinders I provide the middle portion of the floor of the auxiliary combustion chamber with a cinder hopper or outlet D provided with a cover d^1 which normally closes the lower end of the hopper D and prevents the entrance of air at this point. For the purpose of causing the accumulating cinders to flow into the hopper, I provide the lower end of the combustion chamber with inclined walls d^2 extending from the hopper to the sides of the firebox, preferably filling in the corners of the lower part of the auxiliary combustion chamber with refractory material to provide these inclined walls.

Instead of extending the wall retaining plate c^2 continuously from side to side of the firebox, I sometimes divide it into a series of vertically extending portions c^{10} by means of vertically extending slots or cracks c^{11} . I preferably extend the slots or the divisions between the portions c^{10} from the upper edge of the plate downwardly to the shelf c^1 . This formation permits the several sections to accommodate themselves to differences of temperature without producing undue strains in the plate as a whole.

In Figs. 4, 5 and 6 I have illustrated a wall support E which is constructed from a number of vertical sections e^1 . Each section is a single integral piece and includes a portion e^2 of the shelf upon which the wall rests, a portion e^3 forming a part of the wall retaining plate, a portion e^4 forming a part of the depending air directing flange and a portion e^5 forming a part of the floor of the auxiliary combustion chamber a^8 . I provide these sections on their adjacent edges with flanges e^6 by means of which the sections can be bolted together to form a continuous wall supporting or bridge member, the end sections of the series having formed integrally therewith brackets e^7 by means of which the bridge as a whole is adapted to be secured to the sides of the fire box by means of bolts e^8 . This construction of the bridge member provides a bridge, the individual parts of which can be readily handled and placed in position and the individual parts being secured together by means of bolts e^9 in the flanges e^6 . They are more or less flexible and can accommodate themselves to changes of dimensions due to changes of temperature or other causes without producing breaking strains in the bridge member as a whole. The several sections of this form of bridge plate are adapted to be

secured to the wall in the manner described in reference to the preferred form of my invention and each of the sections is provided with a vertically extending brace or rib e^{10} , and with a rib at the rear edge of the shelf 70 portion which serves to retain the lower row of the bricks of the wall upon the shelf.

In Fig. 7 I have illustrated a modified means of retaining the wall in position against the retaining plate. In this instance 75 I provide the plate with vertically extending T-ribs e^{12} on its rear face adapted to coöperate with similarly formed grooves b^{10} in the bricks, the plate and the bricks being adapted to be thereby interlocked together 80 and the bricks thereby retained in position against the plate.

As many modifications of my invention will readily suggest themselves to one skilled in the art I do not limit or confine my 85 invention to the specific structures herein shown and described.

I claim:

1. In a locomotive boiler firebox a vertically arranged cross wall in the forward end 90 thereof extending from side to side and rising from substantially the level of the grate, a metallic wall supporting member extending from side to side, supported by the firebox and retaining the wall in position, said 95 member comprising a horizontal shelf upon which the wall rests and an integral vertically extending wall retaining plate in contact with the formed face of the wall and substantially co-extensive therewith and 100 cap bricks forming the upper edge of the wall adapted to interlock the upper part of the wall and the upper part of the wall retaining plate and means for retaining the lower part of the wall in position on the 105 shelf.

2. In a locomotive boiler firebox a refractory cross wall in the forward end thereof rising from substantially the level of the grate and composed of a plurality of horizontal rows of refractory bricks, a metallic bridge member retaining the wall in position, extending from side to side of the firebox and supported thereby, said member comprising a wall receiving shelf and a 110 vertically extending wall retaining plate, the shelf and the plate being formed integrally with each other, said plate being in contact with the forward face of the wall and substantially co-extensive therewith and 115 refractory cap bricks forming the upper edge of the wall and provided with depending forward ends overlapping the upper edge of the plate, and depending rear ends overlapping the upper edge of the wall 120 whereby the wall and plate are bound together and a vertically extending rib or ledge on the rear edge of the shelf adapted to retain the lower part of the wall on the shelf, the several rows of bricks being pro- 125 130

- vided with interlocking tongues and grooves whereby the intermediate rows of bricks are retained in position.
3. In a locomotive boiler fire box a transverse refractory wall arranged in the forward end thereof and extending from side to side, a metallic bridge member supporting the wall in position and comprising a wall shelf and a wall retaining plate integrally formed together, means for securing said member to the sides of the fire box, the wall having vertically extending air conduits adapted to admit air into the fire box above the grate, the shelf being provided with openings registering with said air conduits and a depending flange or plate on the rear edge of the shelf of a size to extend below the lower end of the fire box and adapted to direct air into said openings.
4. In a locomotive boiler fire box a refractory cross wall arranged in the forward end thereof extending from side to side, a metallic bridge member retaining said wall in position and provided with a horizontal shelf and a vertically extending plate formed integrally with the shelf and adapted to contact with the forward face of the wall, means for holding the wall in position on said bridge member, a vertically arranged depending plate at the rear edge of the shelf closing the forward end of the grate space of the fire box and a forwardly inclined depending plate at the forward edge of the shelf, said depending plates, shelf and vertically extending wall retaining plate being integrally formed, means for closing the space between the forward edge of the inclined plate and the forward end of the fire box and a normally closed cinder outlet arranged between the wall and the flue sheet through which cinders may be withdrawn from the firebox.
5. In a locomotive boiler fire box a refractory cross wall arranged in the forward end thereof extending from side to side and composed of a plurality of bricks arranged in horizontal rows, a metallic wall support spanning the firebox and supported thereby, said support comprising a horizontally extending wall shelf arranged beneath the wall and a buck stay plate formed integrally therewith extending upwardly from the shelf in contact with the forward face of the wall, integral means for retaining the lower rows of bricks upon the shelf and cap bricks interlocking the upper row of bricks with the upper edge of the plate portion, the intermediate rows of bricks being interlocked with the lower and upper rows and thereby retained in position.
6. In a locomotive boiler fire box a refractory cross wall arranged in the forward end thereof extending from side to side and composed of a plurality of bricks arranged in horizontal rows, a metallic wall support spanning the firebox and supported thereby, said support comprising a horizontally extending wall shelf arranged beneath the wall and a buck stay plate formed integrally therewith extending upwardly from the shelf in contact with the forward face of the wall, integral means for retaining the lower rows of bricks upon the shelf and cap bricks interlocking the upper row of bricks with the upper edge of the plate portion, the intermediate rows of bricks being interlocked with the lower and upper rows and thereby retained in position.
7. In a locomotive boiler firebox a refractory cross wall arranged in the forward end thereof extending from side to side and rising from the grate surface, a metallic bridge member retaining the wall in position and comprising a shelf upon which the wall rests and a vertically extending plate substantially co-extensive with the wall and reaching to the upper part thereof and a row of cap bricks on the upper edge of the wall having portions depending in contact with the forward face of the plate and with the rear face of the wall whereby the upper edge of the wall and the upper edge of the plate are bound together.
8. In a locomotive boiler firebox a refractory cross wall arranged in the forward end thereof extending from side to side and rising from the grate surface, a metallic bridge member retaining the wall in position and comprising a shelf upon which the wall rests and a vertically extending plate substantially co-extensive with the wall and reaching to the upper part thereof and a row of cap bricks on the upper edge of the wall having portions depending in contact with the forward face of the plate and with the rear face of the wall whereby the upper edge of the wall and the upper edge of the plate are bound together, said wall being provided with a plurality of vertically arranged air inlet conduits, extending from the lower part thereof and opening through the rear face below said overlapping cap bricks and said shelf being provided with registering openings through which air is admitted to said conduits.
9. In a locomotive boiler fire box a refractory cross wall arranged in the forward end

thereof extending from side to side and rising substantially from the level of the grate, a metallic bridge member retaining the wall in position and comprising a shelf upon which the wall rests and a vertically extending plate substantially co-extensive with the wall and reaching to the upper part thereof, and a row of cap bricks on the wall overlapping the upper edge of said plate, and

means for retaining the cap bricks upon the wall, as and for the purpose specified.

In testimony whereof I have hereunto set my hand, this 27th day of June, 1913, in the presence of two subscribing witnesses.

FREDERICK F. GAINES.
